UNITED STATES PATENT OFFICE.

WILHELMUS ADRIANUS VAN BERKEL, OF ROTTERDAM, NETHERLANDS.

CUTTING-MACHINE.

SPECIFICATION forming part of Letters Patent No. 672,301, dated April 16, 1901.

Application filed October 5, 1899. Serial No. 732,675. (No model.)

To all whom it may concern:

Be it known that I, WILHELMUS ADRIANUS VAN BERKEL, manufacturer, a subject of the Queen of the Netherlands, residing at 68 Bin-
5 nenweg, Rotterdam, in the Kingdom of the Netherlands, have invented certain new and useful Improvements in Meat-Slicing Ma-
chines, of which the following is a specifica-
10 tion, reference being had to the accompany-
ing drawings, in which—

Figure 1 is a side elevation, partly in vertical section, Fig. 2 a plan, partly in horizontal section, and Fig. 3 an end elevation, showing part of a meat-slicing machine having my im-
15 proved knife applied thereto.

With the rotary circular knives of spherical or conical form heretofore employed in cutting or slicing machines good working is attained by causing the knife to come into
20 contact at its beveled part only with the piece of meat, sausage, or the like to be cut, so that it cannot become set fast at the cut-surface of the piece of meat or sausage. This effect is attained according to the present invention with a flat knife or cutting-disk by arranging the said knife so that its axis of rotation is inclined obliquely to the plane of section of the meat, sausage, or the like. The knife or cutting-disk then works likewise with
25 the beveled part only against the piece of meat, while the remaining surface of the knife is removed from the piece of meat.

Referring to the drawings, B is the table for supporting the meat, sausage, or the like, the
35 edge B' of this table forming the plane of section of the meat. The knife or cutting-disk C is mounted with its axis oblique to this plane of section in an oscillating arm A', so that only the beveled part C' comes into con-
40 tact with and acts on the piece of meat—for example, at a gradient of one in ten—the axis Z of the said arm A' being arranged so that the edge of the said knife shall move closely along the edge B' of the table B.

45 The arrangement for supporting the knife C in the arm A' and imparting motion to the said knife is substantially the same as that described and shown in the Letters Patent granted me October 17, 1899, No. 635,225—
50 that is to say, the shaft carrying the knife C is

supported in suitable bearings in the arm A' and is provided with a sprocket-wheel T', which is connected by a chain L to a sprocket-wheel T. The wheel T is connected by a spring-pawl s^4 and ratchet-wheel s^3 to a shaft s, turning in the arm A' and having a pinion z' secured thereon and adapted to gear with a seg-
55 mental rack z^2 , mounted on the frame R² of the machine. By these means the knife can be caused to rotate as the arm A' is depressed 60 by means of the handle E, but remains sta-
tionary as the said arm is raised. In this case, however, the sprocket-wheels T T' should be so arranged that the periphery of the wheel T' lies in the plane of the wheel T 65 at the side thereof at which the chain is tight, the slack side of the chain being at the side of the wheel T' which diverges from the plane of the wheel T. The stretching-roller v' is arranged at the slack side or limb of the 70 chain and serves as a guide therefor.

It is obvious that by arranging the axis of the knife C as above described a setting fast of the said knife in the piece of meat cannot take place, since the surface of the knife op-
75 posite thereto does not come into contact with the meat. By reason of the inclined or oblique position of the knife the cut-off disks or slices of meat or sausage are, however, not flat, but bent. By reason of the softness of 80 the material, however, this is not of any mo-
ment. On the other hand, the arrangement has the advantage that the knife by reason of its flat form can be more easily made than the spherical or conical knives heretofore em-
85 ployed.

What I claim is—

In a meat-slicing machine, the combination with a suitable bed or support and an oscil-
90 lating arm moving in a plane parallel to the end of said bed or support, of an obliquely-
mounted cutting-disk connected to said arm, and means for imparting a rotary motion to said obliquely-mounted disk.

In witness whereof I have hereunto set my 95 hand in presence of two witnesses.

WILHELMUS ADRIANUS VAN BERKEL.
